MACHINE HANDLE

Norman B. Smyers, Brea, Calif.

Application February 3, 1938, Serial No. 188,571

4 Claims. (Cl. 74—548)

This invention relates to an improved machine handle or crank which is likewise equally well adapted for use as a ratchet wrench.

It is one aim of this invention to provide a device adapted to be secured to the feed screw or shaft of any machine which may be fed manually or manually and automatically, especially of the shaper and planer milling machine type.

More particularly it is an object of this invention to provide a handle or crank which will normally remain disengaged from the machine but which may be quickly locked into or released from engagement therewith.

A further aim of the invention is to provide a device that will be actuated into operable engagement when grasped to be operated, and which may be readily adjusted to permanently lock it to the machine when it is desired to use it as a rigid handle or crank.

It is also intended to provide a handle or crank which may be operated as a ratchet or which may be turned in either direction free of the shaft with which it operates or which may turn said shaft in either direction.

Still another aim of the invention is to provide a machine handle which may be used as a socket wrench of the ratchet type.

Other objects and advantages of the invention will hereinafter become apparent from the following specification and from the drawings illustrating a preferred form of the invention, and wherein:—

Figure 1 is a vertical sectional view of the invention shown partly in elevation.

Figure 2 is a similar view of the handle portion of the same showing the levers in a compressed position.

Figure 3 is a vertical sectional view of the opposite end of the invention showing the socket locked against rotation by compression of the levers in Figure 2.

Figure 4 is a horizontal sectional view taken on the line 4—4 of Figure 3.

Figure 5 is a cross sectional view taken on the line 5—5 of Figure 1.

Figure 6 is a cross sectional view taken on the line 6—6 of Figure 2, and

Figure 7 is a vertical sectional view of a modified form of the head.

Referring more particularly to the drawings wherein like reference characters indicate like or corresponding parts in the different views, 10 designates generally the machine handle or crank comprising a head 11, a stem 12, and a handle 13.

Head 11 comprises the segmental sections 14

and 15 provided with the corresponding abutting ears 16 having aligned openings 17 to receive the fastenings 18 by which the sections are secured together. Head 11 is provided with a longitudinally extending bore 19 opening at the upper 5 end of the head 11, and which communicates with an enlarged annular groove 20 disposed intermediate of the ends of head 11.

A socket 21, cylindrical in shape and provided with an annular collar 22 having teeth 23 formed 10 in its periphery, is mounted in bore 19 with the collar 22 positioned in the recess 20. The end 24 of socket 21 projects out of the open end of head 11 and is provided with a recess 25 which extends part of the length of socket 21, and which 15 may be any shape. End 24 is provided with a clamping screw 26 to lock socket 21 to the end of a shaft designated 27, which it is intended to turn as will hereinafter be described, and which the recess 25 is shaped to receive.

The stem 12 is formed integral, at one end with section 14 of head 11. Stem 12 is hollow forming the bore 28 which is restricted at the end adjacent head 11 by the annular inwardly extending shoulder 29. Beyond shoulder 29 bore 25 28 communicates with recess 20. The opposite end of stem 12 terminates in a sleeve 30 arranged substantially at right angles to stem 12. Bore 28 opens into sleeve 30 and is aligned with an opening 31 in the opposite side of the sleeve, for a purpose to be hereinafter described.

Handle 13 is provided with a longitudinal bore 32 which opens at the bottom and extends substantially to the top of handle 13. Corresponding recesses 33 are formed in opposite sides of the 35 lower part of the handle and communicate adjacent their upper ends with bore 32 by means of the openings 34. Handle 13 is provided with a hood shaped portion 35 which is hollow interiorly, and which surrounds the upper end of recesses 40 33. Above hood 35 handle 13 is reduced to terminate in the cylindrical shank 36, adapted to receive sleeve 30 and to be secured thereto by a washer 37 held in position against the upper end of sleeve 30 and shank 36 by the screw 38. Shank 45 36 is provided with an opening 39 communicating with bores 28 and 32.

From the foregoing it will be seen that stem 12 is formed integral with one part of head 11 and secured to handle 13 as just described to connect 50 the parts together. As seen in Figure 1, head 11 and handle 13 are substantially parallel with the former above the latter due to the inclined arrangement of stem 12 as seen.

Mounted in bore 28 of stem 12 is a rod 40 one 55

end of which is guided by shoulder 29 and the opposite end by opening 39. Pivots mounted, on the end of rod 40 which extends through shoulder 29, is a dog 41, which is slidably mounted in recess 28 and which is provided with teeth 42 to engage teeth 23 in collar 22. The opposite end of rod 40 which extends through opening 39 into bore 32 is beveled on its underside at 43. Rod 40, adjacent beveled end 43, is provided with 5 a collar 44 between which and shoulder 29 a spring 45 is held under compression on the rod 40. Spring 45 normally urges rod 40 toward handle 13 to hold dog 41 out of engagement with collar 22 and to project end 43 into bore 32, as 10 seen in Figure 1.

Slidably mounted in bore 32 of handle 13 is a shaft or plunger 46 comprising the upper and lower sections 47 and 48 respectively. Section 47 has its upper end beveled at 49 to face the 20 beveled end 43 and mounted between these beveled faces is a sphere 50 of slightly less diameter than the bore 32. Adjacent the beveled end 49 section 47 is provided with a reduced portion 51, and in its opposite end is formed a recess 52.

The upper end of section 48 is provided with a 25 recess 53 facing recess 52. In these recesses is mounted a coiled spring 54 which normally urges the sections away from each other. Beneath recess 53 section 48 is reduced on one side to form 30 the slot 55 through which extends the pin 56, as best seen in Figure 5. Adjacent the lower end of slot 55 section 48 is provided with an annular groove 57 sized to receive pin 56. Pin 56 restricts the longitudinal movement of section 48 by abutting 35 against the shoulders 58 at the ends of slot 55. When section 48 is in its fully raised position it may be revolved one-half a turn to cause pin 56 to engage groove 57 to lock the section. Spring 54 normally urges section 48 downwardly. The 40 lower end of section 48, which is beneath bore 32, is knurled at 59 to provide a better grip for turning it.

Pivots mounted in hood 35 by means of pins 60 are the levers 61 which extend downwardly, and which are positioned in recesses 33. Levers 61 above pins 60 are provided with the inwardly projecting lugs or ears 62, which have the forked ends 63, as seen in Figure 6. The 45 forked ends 63 extend into the reduced portion 51 of section 47 and abut against the shoulders 64 at each end thereof.

From the foregoing it will be seen that spring 45 normally holds dog 41 out of engagement with collar 22 and urges the beveled end 43 in bore 32 to depress sphere 50 and plunger 47, as seen 50 in Figure 1. When thus depressed, plunger 47 forces ears 62 downwardly to hold levers 61 out of recesses 33. This leaves socket 21 loose so that it can rotate freely in head 11. By gripping handle 13 and the levers 61, the latter will be compressed and move into recesses 33 swinging ears 62 upwardly, raising section 47 and sphere 50 which will project rod 40 to cause the teeth 42 on dog 41 to mesh with teeth 23 to lock socket 21 in head 11 so that the crank 10 will rotate with the shaft 27. If it is desired to retain the parts 55 thus locked, section 48 may be pressed up against the action of spring 54 and rotate a half turn to engage pin 56 and groove 57 to lock head 11 to socket 21 as illustrated in Figures 2 and 3.

In assembling the crank 10 end 43 is held in bore 28 by inserting any suitable instrument through opening 31, while shank 36 is being inserted in sleeve 30. In disassembling, parts 14 60 and 15 are first disconnected and socket 21 re-

65 moved so that dog 41 can be drawn into bore 19 to allow sleeve 30 and shank 36 to be disconnected.

In Figure 7 a modified head designated 11' is 70 shown, wherein the closed end 65 is made in the form of a plug which is removably held by fastenings 66. The recess 20' extends through and opens out of the lower end of the head.

Inasmuch as the machine handle 10 is adapted 75 to be engaged and released by operation of levers 61, a ratchet type crank is provided which can be operated in either direction. Obviously socket 21 could be employed to turn a nut or plug and the device is therefore equally well adapted for use as a socket type ratchet wrench. For such use head 11 or 11' could obviously be inverted if desired.

Various other modifications and changes, such 80 as substituting a frictional engagement between collar 22 and dog 41 for the teeth 23 and 42 respectively, can obviously be resorted to and are contemplated without departing from the spirit 85 and principle of the invention as disclosed, and the right is reserved to make such modifications as fall within the scope of the appended claims.

I claim as my invention:

1. A machine handle comprising a head provided with a recess, a hollow stem extending from said head and communicating with said recess, a handle secured to said stem at an angle thereto, and having a longitudinal bore, a socket provided 90 with an annular toothed collar rotatably mounted in said head, a rod slidably mounted in said stem, a toothed dog mounted on one end of said rod to mesh with said toothed collar, a spring normally urging said dog out of engagement with said collar, the opposite end of said rod extending into the bore of said handle and being beveled on its underside, a shaft formed of two sections 95 slidably mounted in said bore, the upper end of the upper section being beveled to face the beveled end of said rod, a spherical member mounted between and in engagement with said beveled faces, levers pivotally mounted in said handle and having inwardly extending ears to engage the upper section of said shaft to raise it when 100 said levers are compressed to actuate said spherical member to project the rod to lock said dog and collar to rigidly retain the socket in the head, said lower section having a reduced portion on one side forming a slot and a circumferential 105 groove in its opposite side communicating with the lower end of said slot, a pin mounted in the handle and extending through said slot, and means to raise said lower section to align the pin and groove and for turning the lower section to move the groove into engagement with the pin to 110 lock it in a raised position to retain the upper section in a raised position.

2. In a tool of the class described, a head provided with a recess having restricted ends, a 115 socket rotatably mounted in said recess and provided with an annular toothed collar, a stem projecting from said head, a rod slidably mounted in said stem and provided with a toothed dog at one end for engagement with said collar, spring means normally urging said rod away from said head, a handle secured to the opposite end of said stem and provided with a longitudinal bore, the opposite end of said rod projecting into said bore and being beveled on its underside, a shaft 120 slidably mounted in the bore of said handle and provided with a beveled upper end facing the beveled face of said rod, a spherical member disposed between and in engagement with said beveled faces, and levers pivotally mounted in 125

said handle and provided with lugs engaging said shaft, said levers being compressible to raise the shaft to project the rod for engaging said dog and collar.

5 3. A machine handle comprising a recessed head having a hollow stem projecting therefrom and communicating with the recess in said head, a socket rotatably mounted in said head and provided with a toothed collar, a rod slidably mounted in said stem and provided with a toothed dog for engagement with said collar, spring means normally urging said dog out of engagement with the collar, a handle mounted on the free end of said stem, at an angle thereto, and provided with a longitudinal bore, a shaft slidably mounted in said handle, one end of said rod projecting into said handle and disposed adjacent one end of said shaft, said ends being beveled, a spherical member mounted between said beveled faces, and

levers pivotally mounted on said handle and provided with inwardly projecting lugs engaging said shaft for projecting the shaft upwardly when said levers are compressed, to project the rod whereby said dog and collar will be meshed to 5 rigidly hold the socket in the head.

10 4. An article as in claim 3, said shaft being divided transversely, the lower section of said shaft being provided with a reduced portion at one side forming a slot and with a circumferential 10 groove adjacent the lower end of and communicating with said slot, a pin projecting through the bore of said handle and through said slot, and means on the lower end of said last mentioned section for raising it in said bore to align the pin 15 and groove and for turning said section to engage the pin and groove to retain the upper section in its raised projected position.

NORMAN B. SMYERS.
